PRESSING APPARATUS

Johan Daniel Ullgren, Stocksund, Sweden

Application December 14, 1936, Serial No. 115,739
In Sweden December 17, 1935

2 Claims. (Cl. 100—47)

The present invention relates to an improvement in pressing apparatus of the type which are provided with a press roller rotatably journalled in fixed bearings, said roller being surrounded by a ring or drum which is placed eccentrically with relation to the press roller, and the inner diameter of which is larger than the outer diameter of the roller, so that a pressing place or region is formed between the press roller and the ring or drum at that point where the distance between the roller and the ring or drum is smallest. In old pressing apparatus of this type it has proved to be difficult to produce the high pressures required for pressing certain materials, because the supporting rolls which are usually employed for supporting the ring or drum, will only stand a certain limited pressure before the stresses on the material become too high and the surfaces of said rolls become so much worn that they are deformed. Attempts have been made to avoid this difficulty by using a plurality of supporting rolls, but the constructions thus arrived at have not come to practical use because they have been too expensive and unreliable in operation.

The invention has for its purpose to avoid these difficulties and consists principally in the ring or drum being carried by a chain, or chains, or the like, which runs around the ring or drum and over a carrying sheave which is rotatably journalled on the side of the roller opposite to the pressing place or region between the roller and the ring or drum.

This arrangement gives the advantage of providing so large carrying surfaces that no overstrain on the material need be feared, since the pressure on the material being treated is limited only by the pressure permissible on the bearings of the press roller and of the carrying sheave. Means for producing the pressure on the material being treated may suitably be interposed between the bearing of the press roller, on the one hand, and the bearing of the carrying sheave on the other, and may suitably consist of a hydraulic press, i. e., a cylinder with a piston, which is combined with a loaded safety valve for limiting the pressure of the liquid in said press. This entails the advantage that the pressure may be maintained practically constant, and that no damage is caused if too large a quantity of material to be treated, or hard objects such as pieces of iron or the like, happen to be fed into the pressing apparatus.

The accompanying drawing illustrates by way of example a constructional form of the inven-

tion. Fig. 1 shows a side elevation, partly in section, of a pressing apparatus according to the invention. Fig. 2 is a vertical section through the apparatus. Fig. 3 shows a top plan view, partly in section, of the pressing apparatus, the top plate and the hydraulic press being removed. Fig. 4 shows a top plan view of the hydraulic press and associated parts. Fig. 5 shows a detail of a device for controlling the load on the safety valve.

The pressing apparatus illustrated in the drawing, which is primarily intended for pressing out liquid from liquid-containing materials, such as peat, bark, wood pulp, cellulose, and the like, comprises a strong frame 1 in which the press roller 2 is rotatably journalled in fixed bearings 3. The press roller 2 is surrounded by a ring or drum 4, the inner diameter of which is larger than the outer diameter of the roller 2. Said ring 4 is carried by a strong link chain 5 which runs around the ring 4 and over a carrying sheave 6 journalled above the ring. The ring 4 as well as the sheave 6 are provided with grooves 7 and 8, respectively, for guiding the chain 5. Placed on the top plate 32 of the frame 1 is a hydraulic cylinder 9 in which a piston 10 is slideable which carries the bearings 33 of the sheave 6, so that by pumping oil or other suitable liquid into said cylinder 9, the sheave 6 and thus also the ring 4 may be raised relatively to the press roller 2.

For this purpose an oil pump 11 is provided which is driven in a manner described here below, and which draws oil from an oil tank 34 through a pipe 35 and pumps the oil through pipe 36 into the cylinder 9. In order to prevent the pressure in the cylinder 9 from rising above a certain upper limit, a pipe 37 connects the cylinder to a safety valve 16, connected through an oil return pipe 38 to the tank 34. In the instance illustrated, said valve 36 is loaded by weights 17 and 18, so that the valve opens automatically and lets out oil from the cylinder, if the pressure in the latter rises above a certain value which is determined by the weights loading the valve.

Some of these weights, namely the weights 18, are carried by a bolt 19, as shown in Fig. 5, which bolt passes through apertures in the other weights 17. A lever 20 pivoted to the frame at 21, bears against the ring 4 and its free end is positioned below the weights 18. Said lever 20 serves to raise these weights 18, and thus to reduce the load on the safety valve, before the ring 4, when moving upwards under the action of the piston 10, comes in engagement with the press roller 2, so that upon such direct contact occurring between said

members, the pressure is reduced to the amount that the material of the press roller and of the ring can stand without risk. In this manner the pressure is never entirely removed even if the material to be treated is unevenly fed into the apparatus.

The press roller 2 is driven intermittently by means of a ratchet feed device comprising a toothed wheel 23 mounted on the hollow shaft 22 of the roller 2 and engaged by a feed pawl 24 on an eccentric rod 25 which is given a reciprocating movement by an eccentric disk 26 on a shaft 27 journalled in fixed bearings 39 secured to the frame 1. A link 40 connects the rod 25 to the actuating lever 41 of the oil pump 11, whereby said pump is operated by the reciprocating movement of said rod 25. The shaft 27 may be driven by any suitable means, such as a motor, not illustrated in the drawing. Rotatably mounted in bearings 42 on the frame is a supporting roll 30 against which the ring 4 bears, and which serves to guide the ring 4 and to prevent it from moving to the right in Fig. 1.

In the apparatus illustrated, which is intended for pressing out liquid from liquid-containing materials, as previously stated, the circumferential surface of the press roller 2 as well as the inner surface of the ring 4 are provided with comparatively shallow herring-bone-shaped slots 31 which serve to facilitate the flowing off of the liquid pressed out. The herring-bone or angular shape of the grooves or slots also provide the advantage that the grooves do not come into the high pressure region at the pressing place with their full length at once, but with one end before the other. The press roller 2 performs a step by step rotation in the clockwise direction, as viewed in Fig. 1, so that the points of the angular grooves come first to the pressing place. The pressure is then gradually increased along the grooves, so that the liquid can flow off more freely. The flow of the liquid is also facilitated by the above-mentioned intermittent rotation of the press roller.

The material to be pressed is fed, for instance through a chute 43, into the space between the ring 4 and the roller 2 to the right of the latter, as viewed in Fig. 1, and is subjected at the pressing place to powerful pressure between the said members, so that the liquid is forced out of the material. The ring 4 is entrained in the step by step rotation of the roller by the material fed between the roller and the ring. The compressed material may be removed from the ring by any means suitable for the purpose, such as a scraper 44, Fig. 1.

As shown in Fig. 1, the entrance angle to the pressing place is comparatively small, so that the material to be pressed will be securely brought along and subject to a gradually increased pres-

sure for a comparatively long period of time. In this way it is possible to press out the liquid very efficiently, and to obtain a high percentage of dry matter in the material. If too large a quantity of material, or if hard objects such as pieces of iron or the like, happen to be fed into the apparatus, the safety valve 16 opens, so that the ring 4 can move downwards relatively to the press roller 2, thus increasing the distance between said members at the pressing place. In this way the grooves in the press roller and in the ring are protected against damage.

The constructional form above described and illustrated in the drawing is only to be regarded as an example. The term "right," "left," "upper," "lower," etc., are used in a relative sense to simplify the description of the said constructional form. It will be understood that the machine may be modified in several respects as regards its details without departing from the principle of the invention.

I claim:

1. A pressing apparatus comprising a press roller, a rotatable shaft to which said roller is fixed, stationary bearings in which said shaft is mounted, a ring having a peripheral groove and having an inner diameter larger than the outside diameter of said press roller, said ring surrounding said roller and being located eccentrically relative to the same to form a pressing area between said press roller and said ring, a sheave located on the opposite side of said roller to such pressing area, a chain running over said sheave and around said ring, in said peripheral groove, a movable bearing for said sheave, a hydraulic press interposed between said bearing of said press roller and said movable bearing for said sheave to support said latter bearing, a loaded safety valve associated with said hydraulic press to limit the pressure of liquid therein, and a member movable with said ring toward and away from said bearing to vary the adjustment of said safety valve to maintain the load within safe limits.

2. A pressing apparatus comprising side frames, a shaft mounted in fixed bearings therein, a press roller secured to said shaft, positive means for rotating said shaft, a ring surrounding said press roller normally out of contact therewith, between said side frames, a sheave yieldably mounted on said frames, a chain extending over said sheave and under said ring to rotatably support the latter, means normally tending to raise said sheave to reduce the clearance between the adjacent pressing surfaces of said roller and said ring, and a releasing device acting on said means and actuated by a predetermined upward movement of said ring.

JOHAN DANIEL ULLGREN.
